UNITED STATES PATENT OFFICE.

ALBERT BROWNWORTH, OF PHILADELPHIA, PENNSYLVANIA.

FIXTURE.

Application filed October 21, 1925. Serial No. 63,984.

This invention comprehends the provision of a bath room fixture designed to conveniently dispense tooth paste, shaving cream or the like in a quick and sanitary manner, the invention residing in the construction, combination and arrangement of parts as claimed.

In the drawing forming part of this application, like numerals of reference indicate similar parts in the several views, and wherein:

Figure 1 is a sectional view through the device.

Figure 2 is a sectional view on line 2—2 of Figure 1.

Figure 3 is a sectional view on line 3—3 of Figure 1.

Figure 4 is a sectional view on line 4—4 of Figure 1.

Figure 5 is a sectional view on line 5—5 of Figure 1.

Figure 6 is a fragmentary sectional view of a modified construction.

Figure 7 is a plan view of the valve.

Referring to the drawing in detail, 10 indicates a hollow bracket including a base 11 adapted to be secured to a wall or other suitable support, and on which bracket is supported a container. This container includes spaced inner and outer walls 12 and 13, respectively, each of which is closed at its upper end by a cap 14 or 14^a. The bracket is formed with an enlarged portion 15 which constitutes the bottom of the container and includes spaced inner and outer flanges 16 and 17, respectively. The inner wall 12 is threaded into the flange 16 while the outer wall is received by the flange 17 and secured thereto in any suitable manner. The bottom 15 of this container is formed with an outlet opening 18 through which the contents of the container are adapted to be dispensed by means of a spring pressed follower 19 arranged within the container, the spring therefor being indicated at 20. The inner container 12 is probably constructed of glass so it can be conveniently cleaned from time to time, while the outer container or wall 13 is non-transparent and conceals from view the inner container and its contents.

Arranged to operate within the hollow bracket 10 is a combined valve and knife indicated at 21 which is provided with a stem 22 having associated therewith spaced collars 23. Encircling the stem 22 and posi-

tioned within the collars 23 is a coiled spring 24 which functions to normally hold the valve in the position shown in Figure 1, closing the opening 18 of the container. The forward or free edge of this valve is beveled to provide a cutting edge 25 to cut off a strip or portion of the contents of the container forced through the opening 18 by the plunger 19, as will be readily understood. Depending from the valve is a brush support in the nature of a substantially L-shaped bracket indicated at 26 and which includes spaced pins 27 rising from the opposite sides of the bracket to support the brush 28 in the manner shown in Figure 1, the fingers or pins 27 holding the brush against lateral displacement so as to insure proper positioning of the brush beneath the opening 18 to receive the contents of the container. This brush support is also utilized to open the valve against the tension of the spring 24, as it is only necessary to push upon the support after the brush has been arranged thereon. Carried by this support 26 is a bracket 29 including a ring-like portion 30 designed to support a small receptacle 31 directly beneath the brush to prevent any part of the contents falling onto the floor. It will be noted that the bracket 26 is provided with a slot 32 in which the brush support 26 operates, the opposed ends of this slot limiting the movement of the parts.

In Figure 6 I have shown a modified construction wherein the hollow bracket, indicated at 33, is substantially the same as the bracket 10 above described, including the base portion 34 adapted to be secured to a wall or other support. This bracket has formed therewith the bottom 35 of the container including the spaced inner and outer walls 36 and 37, respectively, the former being threaded into the flange 38 of the bottom while the wall 37 is secured in any suitable manner to the flange 39. The bottom is provided with an outlet opening 40 through which the contents of the container is dispensed. A combined valve and knife is indicated at 41 and is adapted to slide through a slot 42 formed in the forward end of the bracket 33 directly beneath the outlet opening 40, and normally held in a closed position by means of a spring 43 which surrounds the stem 44 of the valve, the spring being disposed within the bracket 33 between the spaced collars 45. The valve is

provided with an opening 46 adapted to register with the opening 40 when the valve is opened, one edge of this opening 46 being beveled or sharpened, as at 47, to permit the 5 valve to be used in the capacity of a knife for cutting off a strip of cream or the like as it is forced through the openings 40 and 46, respectively. It will be noted that in this form of the invention the valve is operated by the 10 hand, being provided with a thumb engaging member 48 for that purpose, in contradistinction to the construction and operation shown in Figure 1, wherein the valve is opened through the instrumentality of the 15 brush. In other words, in the structure shown in Figure 6 use of a brush support and also the receptacle shown at 31 in Figure 1 is dispensed with.

While it is believed that from the foregoing description the nature and advantages of the invention will be apparent, I desire to have it understood that I do not limit myself to what is herein shown and described, and that such changes may be 25 resorted to when desired as fall within the scope of what is claimed.

Having thus described the invention, what is claimed as new, is:—

1. A device of the character described comprising a bracket including a bottom having an outlet opening therein and spaced concentrically disposed flanges, an inner container supported within one of said flanges and having an opening in the bottom thereof

registering with the opening in the bottom 35 of said bracket, an outer container supported by the other of said flanges and arranged in spaced relation to the inner container and utilized to conceal the latter and its contents from view, a combined slide valve 40 and knife associated with the bracket and arranged to normally close the opening in the bottom thereof, and a spring pressed follower arranged to operate within the inner container. 45

2. A device of the character described comprising a hollow wall bracket including a bottom having an opening therein, and spaced concentrically disposed flanges, inner and outer spaced containers supported by 50 said flanges, said inner container including a bottom having an opening registering with the opening in the bottom of said bracket, a spring pressed follower arranged to operate within the inner container, a combined slide valve and knife positioned within said bracket and arranged to normally close the opening in the bottom thereof, said bracket having a longitudinal slot, a substantially L-shaped arm projecting through 60 the slot and carried by said valve, and constituting a brush support, spaced lugs rising from the opposite sides of the support and adapted to engage the opposite sides of a brush to hold the latter positioned thereon. 65

In testimony whereof I affix my signature.

ALBERT BROWNWORTH.
